United States Patent Office

Des. 217,772
Patented June 9, 1970

217,772

GRAPHIC TRANSCEIVER

John W. Bruce, Wilton, Conn., assignor to Graphic Sciences, Inc., Danbury, Conn.

Filed Apr. 4, 1969, Ser. No. 16,579

Term of patent 14 years

Int. Cl. D14—01

U.S. Cl. D26—14

FIG. 1

FIG. 2

FIG. 3

FIG. 4

FIG. 5

FIG. 1 is a perspective view of a graphic transceiver embodying my new design;

FIG. 2 is a front elevational view thereof;

FIG. 3 is a left side view thereof;

FIG. 4 is a right side view thereof, and

FIG. 5 is a rear view thereof.

The broken line representation of a telephone in FIG. 1 is for purposes of illustration only.

I claim:

The ornamental design for a graphic transceiver, substantially as shown and described.
